UNITED STATES PATENT OFFICE.

ADOLF BERGNER, OF BERNE, SWITZERLAND.

WIRE-CUTTER.

1,252,537.

Specification of Letters Patent. Patented Jan. 8, 1918.

Application filed August 2, 1916. Serial No. 112,670.

To all whom it may concern:

Be it known that I, ADOLF BERGNER, a citizen of the Swiss Confederation, and residing at Berne, Switzerland, have invented 5 certain new and useful Improvements in Wire-Cutters, of which the following is a specification.

My invention has for its primary object to provide improved wire cutters or the like 10 adapted to be mounted on a bayonet or other suitable weapon and actuated by a thrust.

According to my invention the blades, at 15 least one of which is movable relatively to the other, are mounted on a slide which can be shifted by a thrust exercised counter to the action of a spring against the wire to be cut, whereby the movable blade which is connected with a fixed resistance is moved relatively to the other blade and the wire is 20 thereby cut.

To this end, my invention consists in the construction, arrangement and combination of parts described hereinafter and pointed out in the claims.

25 One illustrative embodiment of the invention and several modifications thereof are represented by way of example in the accompanying drawing, wherein:—

Figure 1 is a side elevation showing one 30 form of wire cutters according to my invention,

Figs. 2, 3 and 4 are like views of modified forms and

Fig. 5 is a detail view.

35 According to Fig. 1, the slide 1 is displaceably mounted on the blade 2 of a bayonet 4 mounted on a small-arm 3. The slide 1 carries a blade 7 of the cutters which runs out in front into a point located close to the 40 sharp edge of the blade 2, so that when the bayonet is suitably placed on the wire to be cut and the small-arm is thrust forward the blade 7 will slide under the wire until the latter abuts against the cutting edge at one 45 end of the other blade 9 of the cutters pivoted on a lug 5 of the slide 1. The other end 10 of the blade 9 is bent outward somewhat away from the blade 7, so that the two 50 blades of the cutters constitute a fork which may be advantageous for rapidly detecting the wire of an entanglement in the dark. The two-armed lever 9—10 constituted by the second blade is pivotally connected to a link 11 and with it forms a knee-joint. The lever 55 arm 10 carries a leaf-spring 12 whose free

end takes over a projection or lug 13 at one end of the link 11 and tends to straighten cut the knee-joint and shift the slide 1 upward as seen in the drawing, whereby the cutters are opened immediately after the 60 wire has been cut and are thus always ready for use. The other end of the link 11 is pivotally held between two lugs 14 of a cap 15 slipped over the pommel of the bayonet. This cap has a downwardly projecting angular lug 16. A bolt 17 is displaceably mounted in the lower horizontal part of the cap and in the part located thereabove. The upper part of this bolt is flat and fits exactly in the groove 18 in the handle of the 70 bayonet. A spring 19 tends to hold the bolt in its upper position, i. e. taking into the said groove, when the cutters are mounted on the bayonet, whereby the cap 15 is securely but detachably held on the handle of 75 the bayonet, as clearly shown in Figs. 1 and 5. When a thrust is exerted by means of the small arm and bayonet on the wire located between the blades of the cutters, after the force of the spring 12 has been overcome, the 80 slide 1 is shifted toward the handle of the bayonet and the knee-joint 10—11 is bent, as shown in Fig. 2. The lever arm 10 is rocked outwardly and the blade 9 inward toward the blade 7, whereby the wire is cut. The 85 resistance offered by the wire is thus used for closing the cutters. As soon as this resistance disappears owing to the wire being cut, the spring 12 straightens the knee joint and opens the cutters. As will be understood from the above it is possible to equip 90 infantry with wire cutters without their being impeded in using the small-arm. As tests have shown, it is readily possible to cut fairly thick wires because a relatively 95 great thrust can be exerted with the small-arm. On pulling the bolt 17 out of the groove in the bayonet handle, the cutters can be immediately removed from the bayonet. Reversely, the cutters can be readily 100 mounted on the bayonet by one single manipulation.

The form shown in Fig. 2 differs from that described above only in the slide 1' being mounted on a stiletto 20 or the like and 105 in the lugs 14', to which the link 11 is connected, being arranged directly on the stiletto. The stiletto terminates at one end in a conical tube 21 and can be attached to any desired rod by means of this tube or in other 110

suitable manner. The operation of this form is the same as that of the form described above.

Fig. 3 shows another modification similar to that shown in Fig. 2 but on a smaller scale. The difference consists solely in the point of the stiletto 20 and the tube 21 being located at the opposite ends. The rod carrying the cutters can be placed over all 10 the wires of a wire entanglement, and the wires can be cut in succession by pulling the rod.

In the modification shown in Fig. 4 the cutters comprise two blades 9, 10 which are pivoted in the slide 1 and pivotally connected by links 11 with lugs 14 on the stiletto 20. The stiletto is inserted into a sleeve 22 and is firmly connected therewith. The sleeve is mounted on the end of a rod 23 by means of which the cutters can be lifted over a wire entanglement, the wires of which can be cut in succession as described above. Owing to the resistance of the wire to be cut located between the two 27 blades 9 the slide 1 is shifted toward the lugs 14, whereby the knee joints 10, 11 are bent still more and the wire is cut.

I claim:—

1. The combination of a support, a slide

movable along the same, a blade carried by 30 the slide, a two-armed lever fulcrumed in the slide, one arm of the lever constituting a second blade adapted to coöperate with the former blade, a link having one end pivotally connected to the end of the second arm 35 of the lever, a spring carried by the second arm of the lever tending to hold the blades apart, and a detachable means on said support having pivoted to it the other end of the said link.

2. The combination of a support, a slide 40 movable along the same, a blade carried by the slide, a two-armed lever fulcrumed in the slide, one arm of the lever constituting a second blade adapted to coöperate with the former blade, a link having one end pivotally connected to the end of the other longer arm 45 of the lever and the other end to the support, and a spring having one end carried by the longer arm of the lever and the other end abutting against the link and tending to hold the blades apart.

In testimony whereof, I affix my signature in the presence of two witnesses.

ADOLF BERGNER.
